UNITED STATES PATENT OFFICE

153,201

DESIGN FOR A POPCORN DISPENSER

William H. Beaudot, Chicago, Ill.

Application January 15, 1948, Serial No. 143,821

Term of patent 14 years

(Cl. D52—3)

To all whom it may concern:

Be it known that I, William H. Beaudot, a citizen of the United States, residing at Chicago, in the county of Cook and State of Illinois, have invented a new, original, and ornamental Design for a Popcorn Dispenser, of which the following is a specification, reference being had to the accompanying drawing, forming part thereof.

In the drawing:

Fig. 1 is a front elevational view of a popcorn dispenser, showing my new design;

Fig. 2 is a side elevational view of the same;

Fig. 3 is a top plan view of the same on a reduced scale; and

Fig. 4 is a rear elevational view of the same on a reduced scale.

The side of the popcorn dispenser not shown is the same in appearance as the side shown.

I claim:

The ornamental design for a popcorn dispenser, substantially as shown and described.

WILLIAM H. BEAUDOT.
